UNITED STATES PATENT OFFICE.

LESTER M. WALDEN, OF CHICAGO, ILLINOIS, ASSIGNOR TO LANSTON MONOTYPE MACHINE COMPANY, OF PHILADELPHIA, PENNSYLVANIA, A CORPORATION OF VIRGINIA.

PERFORATING-MACHINE FOR RECORD-STRIPS.

1,236,891.

Specification of Letters Patent. Patented Aug. 14, 1917.

Application filed January 7, 1915, Serial No. 992. Renewed March 22, 1917. Serial No. 156,736.

To all whom it may concern:

Be it known that I, LESTER M. WALDEN, a citizen of the United States, residing at Chicago, in the county of Cook, in the State of Illinois, have invented certain new and useful Improvements in Perforating-Machines for Record-Strips; and I do hereby declare the following to be a full, clear, and exact description of the same, reference being had 10 to the accompanying drawings, forming part of this specification, and to the figures and letters of reference marked thereon.

This invention relates to improvements in record strip perforating machines, being 15 particularly designed for use in perforating machines for forming record strips which are subsequently used as the controllers for type casting machines. Record strip perforating machines of the character referred 20 to are now commonly employed in connection with the "Lanston monotype" and similar systems for the production or preparation of controllers, such as are employed to govern or control the type making machine in the production of printing characters. An example of a perforating machine 25 in which the present invention may be employed is illustrated in the patent granted to Talbot Lanston, No. 654,115, dated July 17, 30 1900, and inasmuch as the general characteristics of the machine are now well understood and may be ascertained from the aforesaid patent, a portion only of the machine is illustrated in connection with this 35 application.

Referring to the accompanying drawings,—

Figure 1 is a side elevation of the upper portion of the so-called paper tower of the 40 perforating machine;

Fig. 2 is a section in a vertical plane centrally of the portion of the machine illustrated in Fig. 1; and

Fig. 3 is a section showing the nib ex- 45 tractor in elevation.

Like reference characters throughout the several figures indicate the same parts.

The fixed frame of the paper tower is indicated generally in the drawings by the reference numeral 1, and in this frame there is 50 mounted a guide bar 2, in which work a series of punches 3 adapted to move upwardly, each under the control of a finger piece not illustrated herein, but adapted, 55 when depressed, to set in motion mechanism

for advancing one or more of the punches for perforating a strip of paper which is fed over the guide bar and between said guide bar and a curved die located above the guide bar 2 in position to receive a downwardly extending loop of the paper forming the record strip. The paper is fed from a roll such as that indicated at 5 in Fig. 1, around the curved die to a reel 6, the said roll and reel being preferably journaled in 60 supporting bearings at the upper end of the frame 1. The curved die 4 is preferably of 65 more or less cylindrical form and adapted to receive the punchings or nibs removed from the strip of paper by the operation of the punches. Journaled in the frame co- 70 axially with the axis of the curved die is a paper feed shaft 7 having upon it pin wheels 8 and 9 adapted to coöperate with preliminarily formed marginal perforations 75 in the record strip, whereby the rotation of the shaft and pin wheels will accurately feed the paper a definite distance between 80 punching operations.

The portion of the machine thus far described is or may be of the construction now in common use or as described in the patent hereinbefore referred to. With it considerable difficulty has been experienced in getting rid of the punchings or nibs which are 85 forced into the hollow curved die by the punches, the general practice being to provide said hollow die with a top opening through which the nibs or punchings might be removed by a suction apparatus. In ac- 90 cordance with the present invention, however, advantage is taken of the fact that the paper feed shaft passing axially through the hollow die is rotated in the operation of the machine, and a conveyer of the screw type is 95 mounted on said shaft for carrying the nibs or punchings out at one end of the die and through a suitable opening provided for their escape in the frame 1. In the preferred construction the shaft is provided 100 with a sleeve 10 between the pin wheels 8 and 9 and said sleeve is formed with an exterior and relatively deep spiral 11, which will operate to carry the nibs or punchings transversely of the record strip toward one 105 end of the curved die, or toward one of the pin wheels. As shown in Fig. 2, the spiral is arranged to carry the said nibs or punchings toward the pin wheel 9, and at the end of the spiral the said pin wheel is provided 110

with an opening 12, shown in Fig. 3 and in dotted lines in Fig. 2, through which openings the nibs or punchings will pass to the outer side of the pin wheel. To prevent the free escape of the punchings passing through the pin wheel a cylindrical guard 13 is provided on the outer side of the said wheel to bridge the space between the wheel and the frame 1. Said cylindrical guard 13 forms a continuation of the chamber formed by the curved die, and from it the nibs or punchings are discharged through an opening 14 extending diagonally down through the frame 1, where they may be caught in a suitable receptacle such as that indicated at 15. To insure the discharge of the nibs or punchings from the chamber formed by the guard 13, a spiral 16 is secured at one end to the outer face of the pin wheel 9 to operate as a continuation of the spiral 11 on the opposite side of the pin wheel.

With this arrangement, the nibs or punchings are discharged as rapidly as they are forced into the curved die; thus, any accumulation within the latter is prevented, and the operator is relieved of the necessity of giving any attention whatever to their removal. Furthermore, the continuous removal of the punchings as formed prevents any possibility of their getting into the loop of record strip or between the record strip and the die where they are liable to interfere with the proper action of the punches in locating the controlling apertures, or with the proper action of the pin wheels in feeding the strip for coöperation with the punches.

What is claimed is:

1. In a record strip perforating machine, the combination with the frame, die, and series of punches coöperating with the die, of a paper strip feeding mechanism for advancing the paper into position for coöperation with the punches and die, and a conveyer for the nibs or punchings operating in unison with the paper feeding mechanism to carry the said punchings laterally away from the die.

2. In a record strip perforating machine, the combination with the frame, series of punches, and curved hollow die with which the punches coöperate, of a paper feed mechanism embodying a shaft journaled coaxially with the curved hollow die, and a spiral carried by said shaft within the die for feeding the nibs or punchings laterally away from the punches, and to one end of the die.

3. In a record strip perforating machine,

the combination with the frame, a series of 60 punches and die with which the punches coöperate to perforate the record strip, of a paper feed shaft extending longitudinally of the die, pin wheels mounted on said shaft for feeding the record strip, and a spiral 65 movable in unison with the shaft for feeding the nibs or punchings laterally toward the end of the die, whereby they are removed transversely of the strip.

4. In a record strip punching machine, the 70 combination with the frame, and die, of a paper feed shaft, pin wheels mounted on said shaft in position to coöperate with the paper strip at the ends of the die, one of said wheels having an aperture therethrough, 75 and a conveyer mounted intermediate the pin wheels for transferring the nibs or punchings toward the end of the die and in position to discharge through the aperture in the pin wheel.

5. In a record strip punching machine, the combination with the frame, and die, of a paper feed shaft, a pair of pin wheels mounted on said shaft in position to coöperate with the paper strip at the ends of 85 the die, one of said wheels having an aperture therethrough, a spiral conveyer mounted intermediate the pin wheels for transferring the punches into position to discharge through the said aperture in the pin 90 wheel, a guard mounted on the outer side of the last mentioned pin wheel to form a chamber for the reception of the punchings, and a conveyer within said chamber for discharging the punchings therefrom.

6. In a perforating machine for record strips, the combination with the frame having an opening therein for the discharge of punchings, a die, and a rotary paper feed shaft, of a pair of pin wheels mounted on said shaft in position to coöperate with the record strip at the ends of the die, one of said wheels having an aperture therethrough, a spiral conveyer mounted intermediate the pin wheels for transferring the 105 punchings into position to discharge through said aperture in the pin wheel, a guard mounted between the outer side of the pin wheel and frame forming a chamber for the reception of said punchings, and a conveyer movable with the paper feed shaft for discharging the punchings from said chamber through the aperture in the frame.

LESTER M. WALDEN.
